UNITED STATES PATENT OFFICE.

ALEXANDER FERDINAND VICTOR, OF DAVENPORT, IOWA, ASSIGNOR TO VICTOR ANIMATOGRAPH COMPANY, OF DAVENPORT, IOWA, A CORPORATION OF IOWA.

DESIGN FOR A SLIDE FOR STEREOPTICONS.

47,938.

Specification for Design.

Patented Oct. 5, 1915.

Application filed April 2, 1915. Serial No. 18,843. Term of patent 7 years.

To all whom it may concern:

Be it known that I, ALEXANDER FERDINAND VICTOR, a subject of the King of Sweden, having declared my intention of becoming a citizen of the United States, and a resident of Davenport, Scott county, Iowa, have invented a new, original, and ornamental Design for Slides for Stereopticons, of which the following is a full, clear, and exact description, reference being had to the accompanying drawings, forming a part thereof.

My invention relates to a design for slides for stereopticons of an attractive and pleasing appearance.

In the drawings: Figure 1 is a front view of the slide for stereopticons showing my design. Fig. 2 is a horizontal section through the same.

Referring to the drawings, it will be observed that both sides of the slide are the same and that it is rectangular in shape

with the corners rounded, and with its outer margins bounded by a head. It has a rectangular opening, and this opening is bordered by a bead between the pointed corners of which and the outer beaded corners of the slides circular openings appear the edges of which are rolled. As shown in cross-section in Fig. 2 both sides present the same conformation with curved opposed outer margins, flat contacting intermediate portions through which the circular rolled edge openings are formed and inner partially curved and partially straight portions.

What I claim is:

The ornamental design for a slide for stereopticons, as shown and described.

In witness whereof I have hereunto set my hand this 4th day of March, 1915.

ALEXANDER FERDINAND VICTOR.
